UNITED STATES PATENT OFFICE.

WILLIAM BERNARD KNAPP, OF PATERSON, NEW JERSEY.

SCREEN, CURTAIN, AND THE LIKE.

1,198,456.

Specification of Letters Patent. Patented Sept. 19, 1916.

Original application filed September 10, 1913, Serial No. 789,036. Divided and this application filed March 22, 1915. Serial No. 16,034.

To all whom it may concern:

Be it known that I, WILLIAM B. KNAPP, a citizen of the United States, residing at Paterson, in the county of Passaic and State 5 of New Jersey, have invented certain new and useful Improvements in Screens, Curtains, and the like, of which the following is a specification.

This invention relates to curtains, screens 10 and the like and particularly to that class of these devices which are wound on spring rollers, and it consists in certain improvements in the means whereby they are confined to a definite plane of movement in 15 winding on or being unwound from their rollers designed to improve its appearance, increase its efficiency, save space in a window opening or wherever else it may require to be used, facilitate the operation of the 20 screen or curtain and give added strength and durability.

The present application is a division of my application on which issued Letters Patent No. 1,138,668.

25 The invention will be found fully illustrated in the accompanying drawing, wherein,

Figure 1 is a perspective view showing 30 fragments of a screen, the cross-bar attached to the lower edge thereof and one of the guides in which the ends of the cross-bar travel; Fig. 2 is a horizontal sectional view of what is shown in Fig. 1, taken through the cross-bar and guide; Fig. 3 is a horizontal sectional view of an alternative form 35 of the guide; Fig. 4 is a vertical sectional view of the cross-bar; Fig. 5 is a fragmentary view of the screen and a part of the cross-bar attached thereto; Fig. 6 is a plan 40 of the screen; and, Fig. 7 is a fragmentary view of a window, showing my improvement.

The screen *a*, wound on the roller *a'* journaled in the frame *p'*, is provided along its side edge with means to thicken-up the 45 same, as tape, braid, cord or the like material *b* woven into the screen preferably in two spaced parallel rows, the same affording support to the screen against being pulled or working out of its guides, as will 50 appear, and performing certain other func-

tions which are not material in the present instance and are fully explained in my aforesaid application.

To the lower edge of the screen is attached the cross-bar *c*. This includes the sheet 55 metal strip *d* bent longitudinally to form a hollow cross-sectionally rectangular portion *e* having one edge-portion *f* standing vertically and the other edge-portion *g* likewise standing vertically and relatively close to 60 portion *f* and having its edge *h* bent off at right angles to form the channel *i*; said cross-bar also includes the sheet-metal strip *j* having each end split for a short distance inwardly and longitudinally and the portions *k* each side of the split rebent one in 65 one and the other in the other direction, so that each portion *k* grips the side edge of the screen, whose lower edge is folded around the strip *j*, as shown in Fig. 5. The 70 strip *j*, having the screen thus attached thereto, is fitted between the portions *f* and *g* of the strip *d*, whereupon rivets *l* are utilized to secure the parts together.

Each guide *m* for the side edge of the 75 screen and the end of the cross-bar consists of strips *n* of sheet-metal bent longitudinally to form together a cross-sectionally hollow structure affording a slit *o* for the reception of the marginal edge of the screen 80 and the end of the strip *j* (which, it will be noted, forms a projecting fin on the cross-bar)—the slit being too narrow to permit the thickened portions *b* of the screen or *k* of the strip *j* to pass therethrough—and also 85 to form the longitudinal flange *p*, which may project at any desired angle according to the disposition of the surface of the window frame *p'* against which the guide is to be secured, see Figs. 2 and 3, for instance. 90 In the present instance, this flange is formed by folding the edge of one of the strips forming the guide around the edge of the other. I do not wish to be limited to forming the guide of two pieces of metal or 95 otherwise to the precise construction thereof described. The guide is secured in place by screws or the like passed through its flange into the woodwork of the window frame.

For securing the screen at definite eleva¹⁰⁰

tions, a spring-pressed latch in the form of a lever 2, pivoted on a vertical axis in the cross-bar and housed in its channel *i*, may be provided, the outer end thereof projecting normally into overlying relation to the inner face of the guide, which at suitable intervals may have formed thereon or suitably secured thereto the stops *r* each having at one side an inclined and on the other a square-cut face, permitting the latch to snap thereover when the cross-bar is moved in one direction, as in drawing down the screen, but effectually checking its progress in the other direction. In order to elevate the screen, it will be understood that the latches are pressed upon at their inner ends until their outer ends clear the stops *i*.

My construction of the cross-bar and guides involves not only simplicity and durability, without undue cost attending the manufacture and installation of the parts, but it imparts when in place a finish to the window opening and insures facility in the operation of the screen; the cross-bar runs true in the guides *m* not only because its hollow portion *e*, which affords a convenient grip to the operator's hand, obtains an adequate bearing surface against each guide, but because the ends of the strips *j* are confined in the slits *o* formed in said guides, because of the rebent portions *k*, which are somewhat thicker than the slits are wide.

It will be observed that the edge *h*, as well as the hollow portion *e* of the cross-bar, affords a finger-hold for operating the cross-bar. At the back of the ledge formed by the edge *h* the strip *f* upstands somewhat, affording a guard for the screen which protects the latter from being bulged outwardly when the cross-bar is raised or lowered.

Having thus fully described my invention, what I claim as new and desire to secure by Letters Patent is:

1. In combination, the structure having a rectangular opening to be screened and elongated guides at opposite sides thereof, a roller journaled at the third side of said opening, a screen wound on the roller, and an elongated sheet metal part having a hollow longitudinal portion and longitudinal edge-portions arranged in parallel planes and gripping between them the free-end edge of the screen, said part being engaged at its end portions in the guides.

2. In combination, the structure having a rectangular opening to be screened and elongated guides at opposite sides thereof, a roller journaled at the third side of said opening, a screen wound on the roller, and an elongated sheet metal part having a hollow longitudinal portion and longitudinal edge-

portions arranged in parallel planes and gripping between them the free-end edge of the screen, said part being engaged at its end portions in the guides and its hollow portion having its ends adapted to abut said opposite sides of said structure.

3. In combination, the structure having a rectangular opening to be screened and elongated guides at opposite sides thereof, a roller journaled at the third side of said opening, a screen wound on the roller, and an elongated sheet metal part including an elongated sheet metal member and a sheet metal strip having its ends engaged in the guides, the free-end edge of the screen being attached to said strip and the first-named member having longitudinal edge-portions arranged in parallel planes and gripping between them the free-end edge of the screen and said strip.

4. In combination, the structure having a rectangular opening to be screened and elongated guides at opposite sides thereof, a roller journaled at the third side of said opening, a screen wound on the roller, and an elongated sheet metal part including an elongated sheet metal member, having a hollow longitudinal portion, and a sheet metal strip having its ends engaged in the guides, the free-end edge of the screen being attached to said strip and the first-named member having longitudinal edge-portions arranged in parallel planes and gripping between them the free-end edge of the screen and said strip.

5. In combination, the structure having a rectangular opening to be screened and elongated guides at opposite sides thereof, a roller journaled at the third side of said opening, a screen wound on the roller, and an elongated sheet metal part having a longitudinal groove in the relatively inner side thereof, a latch pivoted in the groove, and stops on said structure adapted to be engaged by the latch.

6. In combination, a screen and a sheet metal strip having one edge of the screen extended around the same, and the end portion of the strip being rebent upon the screen and holding the same fastened around the strip.

7. In combination, the structure having a rectangular opening to be screened and elongated hollow guides at opposite sides thereof having longitudinal slits therein, a roller journaled at the third side of said opening, a screen wound on the roller, and a sheet metal strip having the free-end edge of the screen attached thereto, the ends of the strip projecting into said slits of the guides and having rebent portions thicker than said slits are wide.

8. In combination, the structure having

a rectangular opening to be screened and
elongated guides at opposite sides thereof, a
roller journaled at the third side of said
opening, a screen wound on the roller, and
5 a cross-bar having its ends engaged in said
guides and being attached to the free-end
edge of the screen, said cross-bar having a
longitudinal finger ledge on the inner side

thereof and a screen-guard upstanding from
the back of the ledge. 10

In testimony whereof I affix my signature
in presence of two witnesses.

WILLIAM BERNARD KNAPP.
